CIGARETTE CASE

Paul L. McCoon, Los Angeles, Calif., assignor to
 Trijex Corporation, a corporation of California

Application April 25, 1941, Serial No. 390,266

3 Claims. (Cl. 206—41.2)

This invention relates to containing and holding means and has particular reference to means for containing cigarettes for immediate convenient use. A general object of this invention is to provide a simple, practical cigarette case constructed to facilitate the easy removal of the cigarettes and means for removably supporting the case in an automobile or like vehicle to be readily accessible and manipulable by the driver and occupants.

Many automobile accidents have occurred by reason of the driver removing his hands from the steering wheel while searching for a cigarette package in his pockets and while attempting to withdraw a cigarette from the usual paper cigarette package. The locating of the package and the withdrawal of the cigarette not only requires the removal of one or both hands from the steering wheel but distracts the driver's attention from the control of the vehicle.

Another object of this invention is to provide novel means for containing and supporting cigarettes in an automobile or similar vehicle to be readily visible to the driver of the vehicle and to be easy of access and removal by the driver with a minimum of effort and distraction.

Another object of this invention is to provide a cigarette container means that may be easily and quickly secured in practically every make and model of modern automobile without the drilling of holes, without the employment of attaching means not already in the vehicle and without injuring the finish or appearance of the appointments of the vehicle.

Another object of this invention is to provide a holder or bracket readily mounted on the dash of the vehicle by one of the screws of the windshield molding or dash molding to occupy a position where it is readily accessible to the driver of the vehicle and the passengers and yet does not obstruct the view or interfere with the easy access to and operation of the control parts of the vehicle.

Another object of this invention is to provide a holder or bracket of the character referred to that is adapted to receive and dependably hold conventional cigarette packages as well as the cigarette case of the invention.

Another object of the invention is to provide a cigarette case embodying novel and highly effective means for maintaining the cigarettes in condition for easy and immediate individual withdrawal.

Another object of this invention is to provide a cigarette case having parts on the cover and

bottom wall for holding the endmost or outermost free of the other cigarettes and for holding said other cigarettes against premature advancement so that the outermost cigarettes may be withdrawn without interference from said other cigarettes.

Another object of this invention is to provide a cigarette case of the class referred to embodying very effective means for advancing the cigarettes toward the outlet end of the case as the cigarettes are withdrawn which means maintains the cigarettes in upright positions and in an orderly arrangement for successive advancement and withdrawal.

Another object of this invention is to provide a cigarette case of the character mentioned embodying a novel cigarette advancing blade that may be flattened back against the rear wall of the case when the cigarettes are being introduced into the case and that automatically advances the cigarettes across the case toward the forward outlet side until the cigarettes are exhausted, the blade operating to constantly exert a yielding advancement force on the cigarettes in a manner to prevent tipping and dislocation of the cigarettes.

Another object of this invention is to provide a cigarette case that is very little larger than the conventional paper cigarette package in which the cigarettes are marketed and which is operable to readily receive the entire contents of a conventional cigarette package as marketed without necessitating individual handling of the cigarettes. The entire contents of a full package of cigarettes may be simultaneously introduced into the case of the invention by merely starting the entire group of cigarettes into the case from an open end of the package and then sliding the package from the cigarettes while pushing the latter into the case, at which time the advancing blade of the case retracts against the rear case wall.

A further object of this invention is to provide a cigarette case and support therefor for use in an automobile, or the like, that is light in weight and extremely simple and inexpensive to manufacture.

The various objects and features of my invention will be fully understood from the following detailed description of typical preferred forms and applications of my invention, throughout which description reference is made to the accompanying drawing, in which:

Fig. 1 is a fragmentary perspective view of the windshield and molding of an automobile, or the

like, showing the holder or bracket of the invention secured to the molding and supporting the cigarette case. Fig. 2 is an enlarged vertical detailed sectional view of the bracket and case removed from the vehicle showing the case cover in the open position. Fig. 3 is a vertical detailed sectional view taken as indicated by line 3-3 on Fig. 2 and Fig. 4 is an enlarged fragmentary vertical detailed sectional view illustrating another form of spring means that may be embodied in the case.

The present invention, as illustrated in Figs. 1 to 3 of the drawing, may be said to comprise generally, a holder or bracket 10 for ready installation in an automobile or similar vehicle, and a case for the cigarettes removably inserted in the bracket 10 including a case body 11, a cover 12 hinged on the body 11 and a blade 13 in the body 11 for holding the cigarettes C in an orderly upright condition and for advancing the cigarettes across the case for ready removal therefrom.

The holder or bracket 10 is intended to be mounted on a relatively stationary support and is primarily designed to be secured in the driver's compartment of an automobile, truck, or the like. The bracket 10 is shaped and constructed to removably support and hold the cigarette case of the invention; or, if desired, the conventional paper packages of cigarettes, serving to hold either in such a manner that the cigarettes are immediately and readily accessible. In accordance with the invention the bracket 10 is constructed so that it may be quickly and securely attached to the dash board portion of the vehicle by one of the screws 15 of the molding 16 which extends along the upper edge of the dash board.

The bracket 10 is formed of sheet metal, thermoplastic, or similar material having a substantial degree of resiliency. In the preferred construction the bracket 10 is an integral or one piece member and comprises a rear wall 17 and two spaced side walls 18 extending forwardly from the rear wall in spaced apart generally parallel relation. The rear wall 17 may be plain and flat except for an opening 19 adjacent its lower end. The side walls 18 may be flat and substantially vertical and have straight lower edges. The upper edges of the side walls 18 are stepped having forward portions 20 stepped downwardly a substantial distance from the top of the bracket. This cut away or stepped formation of the bracket sides 18 makes the package of cigarettes or the cigarette case readily accessible. Horizontal slots or windows 21 are formed in the sides 18 for the purpose to be later described. Inturned flanges or wings 22 extend along the vertical forward edges of the forwardly stepped lower portions of the side walls 18. The wings 22 lie in a common plane and are substantially parallel with the rear wall 17. Similar inturned generally horizontal flanges 23 extend along the lower edges of the side walls 18. The bracket 10 is proportioned so that the case of the invention or the conventional paper package of cigarettes may be inserted downwardly between the side walls 18 to have its lower end rest on the flanges 23. The cigarette case or package is dependably retained and positioned between spaced side walls 18, the rear wall 17 and the front wings 22.

In accordance with the invention the side walls 18 are formed to grip and hold the case or package through their resiliency. The side walls 18 may be slightly convergent in a forward direction or slightly convergent in an upward direction, or both, to exert a slight gripping force on

the case or package to dependably hold the same and prevent vibration and rattling. The wings 22 may also press inwardly on the forward side of the case or package so that the case or package is gripped between the wings and the rear wall 17. The cut back or stepped side walls 18 expose substantial portions of the case or package to leave extensive forward parts of the case or package fully visible and accessible.

The invention embodies novel means for facilitating the mounting or attachment of the bracket 10. The mounting means adapts the bracket 10 for quick easy attachment to the dash board portion of the vehicle. The improved mounting means includes an upwardly and rearwardly projecting tab or tongue 24 on the back of the bracket 10. The tongue 24 may be an integral continuation or extension of the rear wall 17 turned forwardly and rearwardly at the lower end of the wall. The mounting tongue 24 is shaped and proportioned to bear against the molding 16. In practice the tongue 24 may be shaped to fit against the moldings of practically all makes and styles of modern cars and may have longitudinally extending corrugations 25 to give it increased rigidity. An opening or longitudinal slot 26 enters the tongue 24 from its upper end to receive a selected screw 15 of the molding 16. In mounting the bracket the screw 15 is merely loosened or backed off a suitable distance whereupon the tongue 24 is slid upwardly under the head of the screw 15 so that the screw is received in the slot 26. With the bracket 10 upright and positioned as desired the screw 15 is tightened back down. The opening 19 in the rear wall 17 makes the screw 15 easily accessible for the tightening down operation. The mounting tongue 24 is formed and pitched to support the bracket 10 in an upright position as shown in Fig. 1 when secured to the molding 16, as just described.

The case is adapted to be received and held in the bracket 10 just described and is designed to receive and contain the entire contents of a conventional package of cigarettes. The case body 11 is a socketed or hollow rectangular member comprising a bottom wall 27, front and rear walls 28 and 29 and side walls 30. The case body 11 is preferably an integral or one piece structure and it is preferred to construct the body in whole or in part of transparent material so that its contents are readily visible. The front, rear and side walls 28, 29 and 30 are vertical or normal to the bottom wall 27 and the body 11 is proportioned so that the front, rear and side walls are closely received in the bracket 10. The resilient side walls 18 of the bracket 10 bear inwardly against the case side walls 30 and the rear wall 17 and front wings 22 of the bracket may likewise have gripping and holding engagement with the body 11. The bottom wall 27 of the case body 11 is adapted to rest on the flanges 23.

The case body 11 is proportioned to extend upwardly beyond the upper edge of the bracket 10, there being substantial portions of the side walls 30 and front wall 28 fully exposed and engageable by reason of the stepped formation of the bracket sides 18. In the preferred construction, the upper edges of the side walls 30 curve downwardly and forwardly from a vertical plane about midway between the front and back of the case. This is illustrated in Figs. 1 and 2 of the drawing where it will be observed that the curved upper edges of the case body 11 are spaced a substantial distance above the stepped upper

edges of the bracket side walls 18. The height of the rear wall 29 and the rear portions of the side walls 30 is equal to or greater than the length of a typical cigarette. The sloping or curved forward portions of the side walls 30 leave substantial parts of the forward cigarettes exposed for ready engagement, it being understood that the case is normally closed by the cover 12 which conceals and protects these otherwise exposed portions of the frontmost cigarettes. The case body 11, just described, is light in weight and its walls may be quite thin so that its over all size is only slightly greater than the over all size of a conventional paper package of cigarettes.

The cover 12 is adapted to close the upper end of the case body 11 and is hinged to the body so that it may be swung between the open and closed positions. The cover 12 may be a one piece member of the same material as the case body 11 or of other appropriate material. When the cover 12 is in its closed position it lies parallel with the case bottom wall 17 and has depending side parts 31 and a depending front part 32 for closing the forward portions of the case body 11 left open by reason of the sloping upper edges of its side walls 30. The parts 31 and 32 are adapted to lie flush with the front and side walls 28 and 30 of the case body 11. The side walls 18 and the cooperating marginal portions of the cover 12 and its parts 31 have stepped edges of reduced width which lap one over the other to provide a better seal when the cover is closed and to resist lateral shifting of the cover relative to the case body. The upper end of the case front 28 and the front part 32 of the cover 12 have pitched or sloping cooperating edges.

The hinge for the cover 12 includes a hinge pin 33 passed through openings in the side walls 18 and having its end parts received in ears 34 on the cover 12. The ears 34 are received in recesses or pockets in the upper rear corners of the case body 11. A stop ridge 35 may extend downwardly along the rear edge of the cover 12 to engage the rear wall 29 of the case body for the purpose of limiting the opening movement of the cover. The cover 12 is preferably stopped in a fully raised or opened condition such as illustrated in Fig. 2. Means are preferably provided for normally holding the cover 12 in its closed position. This means includes a catch 36 in the form of an outstanding ridge on the upward forward faces of the front wall 28 and a hook-like latch 37 on the lower edge of the cover part 32, which is adapted to spring or snap into or out of holding cooperation with the catch 36. The resiliency of the material of which the case body 11 and cover 12 are formed normally holds the latch 37 in cooperation with the catch 36 and provides for the proper latch operation.

Spring means is provided for moving the cover 12 to the open position upon the release of the latch 37 and for holding the cover open until deliberately closed. A torsion spring 38 is engaged on the hinge pin 33 and has one end part 39 bearing flatly against the inner surfaces of the rear wall 29 and having its other end part 40 bearing outwardly against the under side of the cover 12. The spring part 40 may be held in place by a ridge 41 on the under side of the cover 12 which engages about it. The spring 38 is normally under torque to constantly exert a raising force on the cover 12 and upon the re-

lease of the latch 37 the cover swings upwardly to its full open position.

The case body 11 and the cover 12 have parts cooperable with the cigarettes C to assist in freeing and isolating the foremost cigarettes from the other cigarettes in the case to facilitate their ready removal without binding. An upstanding transverse ridge 42 is formed on the bottom wall 27 in spaced generally parallel relation with the front wall 28. The ridge 42 is positioned to be received between the first and second rows of cigarettes C and is formed and positioned to hold the lower portion of the second to the foremost row of cigarettes C out of engagement with the foremost row of cigarettes. As illustrated in Fig. 2 of the drawing, the ridge 42 may hold the bottom portion of the second to the foremost cigarettes from moving forward and to prevent said cigarettes from binding against the foremost cigarettes. This leaves the foremost cigarette free to be withdrawn without interference from the other cigarettes and prevents unwanted movement or displacement of the other cigarettes when the forward cigarettes are withdrawn.

The under side of the cover 12 has a pair of spaced transverse ridges 43. The ridges 43 are located to engage downwardly against the upper ends of the second row of cigarettes C and the third row of cigarettes C. When the cover 12 is closed the ridges 43 serve to break or release the adhering engagement of the cigarettes one with the other, this being particularly true in the case of the front row and the second to the front row of cigarettes. The ridges 43 also serve to prevent premature forward advancement of the cigarettes under the action of the blade 13 and prevent tipping or tilting of the cigarettes from the vertical positions, and at the same time assisting in maintaining the cigarettes in regular rows.

The blade 13 serves to advance the cigarettes C forwardly in the case as the cigarettes are successively withdrawn and operates to maintain the cigarettes upright and in a compact group so that they do not fall or tip to inclined positions where they might become bent or broken. The blade 13 is a thin flexible resilient member initially or normally bowed longitudinally. The upper end of the blade 13 is pivotally supported or hinged at the hinge of the cover 12 and the blade is arranged to have its convex side face forwardly to act on the cigarette C. Tubular or rolled parts 44 are formed on the upper edge of the blade 13 and are engaged on the hinge pin 33 to pivotally suspend the blade. In the form of the invention illustrated specifically in Figs. 2 and 3 of the drawing the spring 38 for elevating the cover 12 has an arm 45 continuing or extending from its part 39 for acting on the blade 13. The arm 45 is an integral continuation of the spring part 39 and is shaped and disposed to normally tend to swing upwardly and forwardly through its inherent resiliency. The spring arm 45 acting forwardly and upwardly against the upper portion of the bowed blade 13 actuates the blade in the most effective manner. The spring actuated resilient blade 13 presents a curved or convex active face which bears against the rearmost row of cigarettes C in a plane spaced a substantial distance above the lower ends of the cigarettes and this spring pressure maintains the cigarettes in a compact orderly group and advances the cigarettes to the forward end of the case for removal.

When the case is being filled the blade 13 is pressed rearwardly to lie substantially flat against the rear wall 29 to occupy a minimum of space and to permit the free entry of the full package of cigarettes. In this connection it will be observed that the spring part 38 is recessed or inset in the rear wall 29 and that the rolls 34 and the hinge pin 33 are received in a recessed upper corner of the wall 29 so that the case parts do not interfere with the flat retraction of the blade 13 against the rear wall 29. When the blade 13 is retracted against the rear wall 29, as just described, the spring arm 45 likewise retracts and lies flat against the wall 29.

Fig. 4 of the drawing illustrates a slightly modified form of construction wherein a separate spring 50 is employed to actuate the blade 13. In this construction the spring 38 may be as described above with its parts 39 and 40 bearing against the rear wall 29 and the under side of the cover 12, respectively. The spring 50 is engaged on the hinge pin 33 in adjacent relation to the spring 38, the two springs being received between the spaced tubes or rolls 44 of the blade 13. The spring 50 has one projecting end part 51 bearing rearwardly against the rear wall 29 and has a longer part 52 on its other end bearing forwardly against the rear side of the blade 13. The spring part 52 operates in the same way as the above described arm 45 to urge the flexible resilient blade 13 forwardly against the cigarettes C.

It is believed that the utility and practicability of the cigarette case and bracket for the same will be readily understood from the foregoing detailed description. The bracket 10 may be very easily and quickly secured in the selected position in the driver's compartment to be fully accessible to the driver. The bracket 10 is secured in place by one of the screws 15 and does not require the employment of additional securing means, such as clamps, bolts, or the like. The case may be loaded with the cigarettes before or after its arrangement in the bracket 10. In loading the case the latch 37 is released and the cover 12 is allowed to swing open to expose the empty interior of the case body. One half of the original paper package is then removed and the cigarettes are started from the package. The projecting portions of the group or bundle of cigarettes is started in the upper end of the case body 11 and the cigarettes are pushed half way into the case. The flexible side walls 30 of the case body 11 are then compressed or pressed inwardly to grip the cigarettes C and the bottom half of the paper package is removed. The cigarettes C are then fully pushed into the case. These operations, of course, retract the blade 13 and the blade lies close against the rear wall 29 but is urged forwardly against the cigarettes C by its own resiliency and by the action of the arm 45 or the spring part 52, as the case may be. As illustrated in Figs. 3 and 4 of the drawing the blade 13 is sufficiently wide to act on the two rows of cigarettes so that an even pressure is maintained on all of the cigarettes C.

The cover 12 may be normally kept closed. When it is desired to obtain a cigarette the latch 37 is released so that the cover 12 swings open. This exposes the upper portions of the cigarettes occupying the forward part of the case. The driver of the vehicle or the passengers may withdraw the cigarette with great ease. As the cigarettes are successively withdrawn the resilient spring urged blade 13 advances the remaining

cigarettes toward the front of the case. The blade is shaped and mounted to maintain the cigarettes in an upright condition and the ridges 42 and 43 assist in this respect. The foremost cigarettes are always upright and free for immediate removal. If desired, the case may be withdrawn from the bracket 10 to be carried in the pocket or elsewhere. The case is only slightly larger than the conventional paper package of cigarettes and is suitable for carrying in the pocket or pocket book. When the case is formed of transparent material the cigarettes C are visible and when the case is carried in the bracket 10 the slots 21 permit the driver to determine the number of cigarettes remaining in the case.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. A cigarette case comprising a case body having front and rear walls, a bottom wall and spaced side walls, the upper edges of the side walls sloping downwardly to the front wall to leave the upper parts of the cigarettes in the forward portion of the case exposed and accessible, an upstanding ridge on the bottom wall extending transversely of the bottom wall and spaced from the front wall to engage between the front row and the second to the front row of cigarettes, said ridge serving to hold the lower parts of said second to the front row clear of the front row and to maintain the cigarettes in rows, the ridge being low and shaped to allow advancement of said second to the front row when the cigarettes of the front row have been withdrawn from the case and means for advancing the cigarettes forwardly toward the front of the case as the forward cigarettes are withdrawn.

2. A cigarette case comprising a case body having front and rear walls, a bottom wall and spaced side walls, the upper edges of the side walls sloping downwardly to the front wall to leave the upper parts of the cigarettes in the forward portion of the case exposed and accessible, a hinged cover for the case body, and a ridge on the under side of the cover for engaging the upper end of the second to the front row of cigarettes when the cover is closed to release the adhering engagement of the front row and said second to the front row of cigarettes.

3. A cigarette case comprising a case body having front and rear walls, a bottom wall and spaced side walls, the upper edges of the side walls sloping downwardly to the front wall to leave the upper parts of the cigarettes in the forward portion of the case exposed and accessible, a hinged cover for the case body, ridges on the under side of the cover for engaging the upper ends of the second and third rows of cigarettes when the cover is closed to release the adhering engagement of said rows and to release the adhering engagement of the front and said second to the front rows of cigarettes and a ridge on the bottom wall of the case body for engaging between the forward rows of cigarettes, the last named ridge extending transversely of the bottom wall and spaced rearwardly from the front wall and being low and shaped to allow advancement of the remaining cigarettes when the cigarettes of said front row are withdrawn from the case.

PAUL L. McCOON.
